VEHICLE DOOR CONTROL

Charles A. Breit, Houston, Tex.

Application April 24, 1933, Serial No. 667,580

8 Claims. (Cl. 303—6.1)

This invention relates to vehicle door control. An object of the invention is to provide controlling means for vehicle doors, such as are designed for use on street cars, buses and the like, and which are arranged to be manually opened by the passenger and automatically closed, but which can be opened only when the vehicle brakes are applied and which must be completely closed before the brakes can be released.

10 Another object of the invention is to provide mechanically operable means normally locking the doors in closed position, said locking means being releasable electrically by means of an electrically operable releasing device under the control of the vehicle operator.

Another object of the invention resides in the provision of mechanical means for maintaining the locking device in inactive position when the doors are open and which is moved to inactive or neutral position when the doors are closed to permit the locking device to move to active position to lock the doors in closed position.

A further object of the invention is to provide an apparatus of the character described with a warning signal, such as an electric light or other electric signal, operative to notify the vehicle operator when the doors are open and when in closed position.

A further feature of the invention resides in the provision of electrically controlled means under the control of the operator and through which the release of the vehicle brakes will be prevented until the doors are fully closed.

With the above and other objects in view, the invention has particular relation to certain novel features of construction, operation and arrangement of parts, an example of which is given in this specification and illustrated in the accompanying drawings, wherein:

40 Figure 1 shows a side view of the vehicle doors as viewed from the inside of the vehicle.

Figure 2 shows a top view of the doors, showing the connecting mechanism for causing the simultaneous movement of the doors and the closing door check.

Figure 3 shows a fragmentary detail of said check, showing the actuating spring.

Figure 4 shows a fragmentary vertical sectional view of the vehicle showing also the wiring diagram, and

Figure 5 shows a fragmentary detail of the air control valve mechanism.

Referring now more particularly to the drawings wherein like numerals of reference designate the same parts in each of the figures, the numerals

1 and 2 refer to the doors which are fastened at their outer edges to the vertical rotatable supporting shafts 3 and 4 suitably mounted in the vehicle. Cranks 5 and 6 are securely fastened to the upper ends of these respective shafts and extend in opposite directions and are connected by the cross link 7 whose ends are pivotally connected to the ends of said respective cranks so that when either door is opened or closed the other door will move correspondingly so that the doors will open and close together. There is a conventional type of door closing check 8 which is pivotally mounted at one end to the free end of an extension 5' of the crank 5 and the other end of this check is pivotally connected to the lug 10 which is fastened to the link 1. The door check 8 includes also a helical spring 9, shown in Figure 3, which normally tends to maintain the doors in closed position. The vehicle has a pivotally mounted latch as 12 over one of said doors as 2. 15 The outer end of this latch is pivoted to a suitable part of the vehicle at 12'. The lower end of a link 13 is pivoted to the latch 12 and its upper end is connected to an armature 15 of the electromagnet 14 above. The door beneath the latch 12, 20 has an inwardly extending bracket 11 attached thereto whose inner end is upturned and the bracket is so located that the inner free end of the latch 12, will drop in behind said upturned end when the doors are closed, and will lock the doors 25 in closed position.

Secured on the outside of the door 2 there is a bracket 39 which overlaps the door 1, on its outer side as shown in Figure 1. This prevents the opening of the door 1 until the door 2 has been released and upon release of the latch 12, should the passenger push the door 1 outwardly the door 2 will immediately swing outwardly also. Were it not for the bracket 39 the door 1 would have a certain amount of swinging movement independent of the door 2 on account of necessary looseness of connections between the cranks 5, 6 and the cross link 7.

Supported on the latch 12 there is an electric switch 18 shaped to complete electrical connections with the spaced contacts 17 above before the latch 12 clears the upturned end of the bracket 11 to unlock the doors.

There is a depending swinging hook 19 whose upper end is pivoted at 20 to a suitable part of the vehicle, said hook being arranged so that its free end will normally rest against the upturned end of the bracket 11 and when the latch 12 is lifted and the door is opened this hook will swing by gravity underneath the free end of the latch

in position to maintain the latch in inactive or unlocked position.

The numeral 30 designates a fluid pressure line connected with a suitable source of pressure fluid 5 and which enters the chamber of a casing 39'. This casing 39' has an outlet conduit 40 which connects with the pipe 28. The lower end of the conduit 40 is formed with a valve seat 41 arranged to be closed by the valve 42 which is seated 10 by the coil spring 43 and which normally holds the valve 42 closed. There is an electro magnet 29 whose armature 44 is formed with a valve 45 arranged to control a valve seat 46 and when seated to close the conduit 40. The valves 42, 15 45, are connected by a stem 47 arranged within the conduit 40. The pipe 28 is connected into the casing 48 of the air release valve mechanism and slidably mounted in this casing 48 is the double check valve 25. The vehicle will be 20 equipped with the usual control valve accessible to the operator and which may be manipulated by the operator to admit air through the lines 26, 27, to the brake cylinders for the purpose of setting the brakes, the double check valve 25 25 meanwhile moving to the position shown in Figure 4 to close the pipe 28 and open the pipe 27. If a passenger desires to alight from the car, the operator may close the switch 23 and an electrical current will flow through the conductor 31, 30 the electro-magnet 14 and will ground on the vehicle at 48. Thereupon the armature 15 will be lifted elevating the latch 12. The contacts of the switch 18 will thereupon make connections with the contacts 17 before the latch 12 is fully 35 lifted and disengaged from the bracket 11 and thereupon current will flow through the conductor 32 and switch 18 to conductor 33 and thence divides and flows through the conductor 34, energizing the electro-magnet 29 and being 40 grounded on the vehicle at 49, said current flowing also through the conductor 35 and the electric signal 24, and being grounded on the vehicle at 50.

The electro-magnet 29, being energized, actuates the armature 44 opening the valve 42 and closing the valve 45 and communicating the pipe 30 with the pipe 28. Should the operator now attempt to release the brakes before the doors are closed the pressure will be relieved from the pipe 26 and the double check valve 25 will move to left hand position under the influence of pressure from the pipe 28, cutting off escape of pressure from the brakes through the pipes 26 and 27 and supplying pressure to the pipe 27 from the pipe 28 thus maintaining the brakes in set position to the end that the operator can not release the brakes while the doors are unlocked.

The latch 12 will continue to move toward inactive position after the switch 18 has completed connections with the contacts 17, the spring 52 yielding to permit this, until the latch 12 has released the bracket 11, that is has moved to inactive position. The doors are free to be pushed open by the outgoing passenger and the opening movement of the doors will be restrained only by the spring 9 of the door check 8. The initial movement of the door 2 allows the hook 19 to pass under the free end of the latch 12 which prevents the latch 12 from dropping when the doors are opened even though the operator should open the switch 23, and so the switch 18 will remain in contact with the contact points 17 and the signal 24 will be rendered active and the brakes will be applied as long as the door is held open regardless of the manipulation of the switch 23.

When the doors are released by the passenger they close due to the force of the spring 9 but the check 8 retards the closing movement of the doors so that they will not suddenly close. The sequence of locking operation depends on the position of the switch 23. If this switch is closed with the armature 15 and latch 12 being held elevated by the electro-magnet 14 the door bracket 11 merely pushes the hook 19 out from under the end of the latch 12 and the door is not locked until the switch 23 is open to permit the latch 12 to drop by gravity. If the switch 23 is open when the doors swing to closed position the bracket 11 will release the hook 19 from the latch 12 and said latch immediately drops to active or locking position opening the switch 18 which, in turn, renders the signal 24 inactive and de-energizes the electro-magnet 29. Thereupon the spring 43 will close the valve 42 shutting off the pressure pipe 30 from the pipe 28 and said pipe 28 will be vented to atmosphere through the seat 46 thus restoring the normal control of the brakes to the operator.

The main electric supply line is indicated by the numeral 52 which is equipped with a cut out switch 21 and a fuse 22.

The numerals 36, and 37, designate resistors in the conductors 35 and 34 respectively, and which are necessary only when high voltage current is used.

The numeral 38 designates a resistor connected into a current conductor 53 to limit the amount of current required to hold the armature 15 up while the doors are open and the switch 23 closed. The electro-magnet 14 is so constructed that the armature 15 opens the switch 18 just before said armature completes its upward movement thus causing the resistor 38 to be connected in series with the coil of the magnet 14 thereby reducing the amount of current. This unit, or electro-magnet, 14, as a whole, is of conventional construction. In cases where current of low voltage is available, the resistor 38 is not necessary but a coil of high resistance may be used as a part of the electro-magnet 14.

The drawings and description disclose what is now considered to be a preferred form of the invention by way of illustration only while the broad principle of the invention will be defined by the appended claims.

What I claim is:

1. A vehicle door mounted to open and close, means for automatically closing the door, means movable to active position to lock the door in closed position and movable to inactive position to release the door to permit the door to be manually opened, means under the control of the operator of the vehicle and effective, when manipulated, to move said locking means to said inactive position and brake controlling means arranged to be controlled by the operator-controlled means and effective to admit a continuous pressure of fluid to the vehicle brake mechanism to maintain the vehicle brakes set while the door is unlocked.

2. A vehicle door mounted to open and close, means for automatically closing the door, means movable to active position to lock the door in closed position and movable to inactive, or unlocked position, to release the door to permit the door to be manually opened, means arranged to be rendered active by the vehicle operator and effective to move said locking means to said inactive position to release the door and also arranged to be rendered inactive by the operator

- to permit the locking means to move to active position to lock the door closed, and brake controlling means arranged to be controlled by said operator-controlled means and effective to continuously admit fluid pressure to maintain the brakes set when said door-locking means is in released position. 5
3. A vehicle door mounted to open and close, means for automatically closing the door, a locking device movable to active position to lock the door closed and movable to inactive position to release the door to permit the door to be manually opened, operator-controlled means operative, by the vehicle operator, to active position 10 to release said door-locking device and to neutral position to permit said door locking device to assume its said active position to lock the door closed, an electric signal device affected by the operator-controlled means and effective to indicate the position of said door-locking device, and 15 brake controlling means arranged to be controlled by said operator-controlled means and effective to continuously supply a pressure fluid to the brake mechanism to maintain the brakes set when said door locking device is in released position. 20
4. A vehicle door mounted to open and close, means for automatically closing the door when the door is opened, a locking device movable to active position to lock the door closed and movable to inactive position to release the door to permit the door to be manually opened, operator-controlled means operable by the vehicle operator and effective to release said door locking 25 device, an electric signal device affected by the operator-controlled means and effective, when so operated, to indicate that the door is released, brake controlling means arranged to be controlled by the operator-controlled means and effective to set the brakes when the door is so released and means for maintaining said signal and for maintaining the brakes set when the locking device is in inactive position. 30
5. In a vehicle having a device for controlling the application of fluid under pressure to the 35 brakes of the vehicle, a barrier mounted to be manually opened, means for automatically closing the barrier, means normally locking said barrier in closed position, electrically operable means under the control of the operator through which 40 said locking means may be released to unlock the barrier, brake controlling means arranged to be controlled by said operator-controlled means and effective to maintain the brakes set when the barrier is unlocked and to prevent the release of the 45
- brakes when the barrier is opened, said operator-controlled means being operative to permit the barrier to be locked and the brakes released, only when the barrier is fully closed. 50
6. A vehicle barrier mounted to open and close, means for automatically moving the barrier to closed position, when open, said barrier and an adjacent part of the vehicle being provided one with a fixed and the other with a movable interlocking means, said interlocking means being 10 adapted to interengage to lock the barrier in closed position, means mounted independent of the barrier but operable in response to the barrier movements and arranged to automatically engage the movable interlocking means when the latter is released to hold said interlocking means in released position, said fixed interlocking means being arranged to release said holding means upon closing of the barrier to permit the interlocking means to interengage to lock the barrier 15 closed. 20
7. A vehicle barrier mounted to open and close, means for automatically moving the barrier to closed position when open, said barrier and an adjacent part of the vehicle being provided with 25 interlocking means, said interlocking means comprising relatively movable parts one of which is movable to inactive position to release the barrier to permit the barrier to be opened and to active position to lock the barrier in closed position, 30 means under the control of the vehicle operator for moving said part to said inactive position, a holding device mounted independent of the barrier normally held inactive by one of said parts and automatically movable into active position 35 upon opening of the barrier to engage and maintain the other part in said inactive position while the barrier is open. 40
8. A vehicle barrier mounted to open and close, means for moving the barrier when open to closed 45 position, said barrier and an adjacent part of the vehicle being provided, one with a fixed, and the other with a movable interlocking means, said interlocking means being adapted to enterengage to lock the barrier in closed position, a movable member mounted independent of the barrier and arranged to automatically engage the movable interlocking means when the latter is released to hold said interlocking means in released position, said fixed interlocking means being arranged to release said holding device upon closing of the barrier to allow the interlocking means to interengage to lock the barrier closed. 50

CHARLES A. BREIT. 55
